UNITED STATES PATENT OFFICE.

HANS FOMM, OF LEIPZIG-REUDNITZ, GERMANY.

COLOR-PRINTING PRESS.

SPECIFICATION forming part of Letters Patent No. 773,009, dated October 25, 1904.

Application filed April 22, 1904. Serial No. 204,347. (No model.)

To all whom it may concern:

Be it known that I, HANS FOMM, a subject of the German Empire, residing at 7 Kohlgartenstrasse, Leipzig-Reudnitz, Germany, have invented certain new and useful Improvements in Color-Printing Presses; and I do hereby declare the following to be a full, clear, and exact description of the invention, such as will enable others skilled in the art to which it appertains to make and use the same.

This invention relates to an improvement in color printing and stamping presses by means of which it is possible, according to the nature of the colors and printing-plates employed, to apply color to the plates either once or twice before each printing without any greater attention being required from the printer or layer-on in the latter case.

In the color printing and stamping presses constructed in the manner of toggle-lever presses it often happens that very troublesome colors are used which do not readily adhere to the brass types, for which reason the laying-on of the color has to be repeated. Consequently in presses of the kind mentioned this operation is encountered by many difficulties, as all the working operations—such as the laying of the color on the printing-plate, the running-in of the carriage, the printing; and hereupon the running-out of the printing-plate—must be completed with a single revolution of the main shaft, so that an increase in the number of the color-rollers and a consequent necessary enlargement of the color-roller course is impossible owing to a lack of time. For this reason the repeated laying of color on the printing-plates in color printing and stamping presses can only be effected by temporarily stopping the run-out sliding carriage and plate, so that at its next revolution the main shaft will set all parts of the machine in motion except the carriage, but only the color-rollers will actually work. Devices of the kind are already known in connection with color printing and stamping presses, but only imperfectly fulfil their purpose, as they require that at the given time the printer shall couple or uncouple the sliding carriage with the carriage-actuating device by hand.

As distinguished from the above, in the

present invention the coupling and uncoupling of the sliding-carriage-actuating gear is effected automatically, so that the run-out carriage and plate is automatically stopped at the beginning of the next revolution of the main shaft and hereupon immediately coupled again automatically, so that the printer has no more work to perform than in working easy colors which do not require to be laid on more than once.

60 The invention is illustrated by way of example in the accompanying drawings.

Figure 1 is a side elevation of the color-printing press with run-out sliding carriage immediately before the uncoupling begins; Fig. 2, a partial plan of Fig. 1; Figs. 3 and 4, details, Fig. 3 showing the position of the uncoupling device when the carriage is released and Fig. 4 the position during the printing movement. Fig. 5 is a side elevation showing the inking mechanism.

70 The sliding carriage *a* is linked in the usual way to the oscillating levers *d* by means of the connections *b*, which are supported by the fixed bolts *c*, Figs. 2, 3, and 4, and are actuated by means of the eccentric disks *m m'*, fixed on the main shaft, through the medium of the connecting-rods *g* and the levers *h* oscillating around the pins *i*. The connecting-rods *g* instead of having the usual closed lugs 75 are provided with catches notched underneath to form gabs, which engage pins *n*, Fig. 2, in the oscillating levers *d*. Both connecting-rods *g* are supported by arms *k*, which are pivotally connected with the transverse shaft *o*, this latter being supported in turn by the arms *p*, fixed on the shaft *r*. The shaft *r* is actuated by means of a cam-disk *s*, with toothed periphery and gearing, with the wheel *q* of the main shaft *w*. With the cam *s'* the pin *t*, Fig. 3, of the lever *v*, attached to the shaft *u*, engages. The shafts *u* and *r* are connected by means of toothed segment-levers *y* and *z*. It should further be mentioned that the cam-disk *s* has twice as large a diameter as the wheel *q*.

80 When the uncoupling device is put into engagement, the following working operations are effected: If the machine, with the sliding carriage run in, has executed a printing move-

ment and thereupon the run-out carriage *a* has reached its extreme position, Fig. 1, the segment-lever *y* is caused by the cam-disk to swing downward and the shaft *r* correspondingly rotated, so that the arms *p*, with the supporting-arms *k* and connecting-rods *g*, are moved upward, whereby the catches in the connecting-rods leave the pins *n*, Fig. 3, so that upon the shaft further rotating the oscillating arms *d* cannot participate in the movement of the parts of the machine, which with the exception of the coloring mechanism *x*, Fig. 5, are running idly. Only when the main shaft *w* has finished its second revolution are the connecting-rods *g* lowered by the action of the cam-disk *s* and so connected with the oscillating arms *d* that the carriage *a* is pushed in for the following printing.

The device for automatically raising and lowering the connecting-rods *g* is only illustrated by way of example, as the mechanism required for the purpose may be of very varied form. All that is necessary is that the connecting-rods *g* should lie with their gabs on pins *n* of the oscillating levers *d* and be connected by means of supporting-arms *k* and levers *p* with the shaft *r*, to which at a given time a motion is imparted by means of a part of the machine, which only rotates once while the main shaft *w* rotates twice, so that the connecting-rods *g* are released or engaged.

In order that the machine may also be employed for lighter printings, which do not require a second laying on of color, the automatic coupling and uncoupling device should be constructed so that it can be put out of ac-

tion. In the form illustrated this can be effected by simply removing the pin *t* from the cam *s*.
40

What I claim, and desire to secure by Letters Patent, is—

1. In a printing-press, in which the printing-plate is carried on a reciprocating carriage, oscillating levers *d* adapted to reciprocate the carriage, pins *n* on the levers, connecting-rods *g* provided with gabs which engage the pins, and means for automatically disconnecting the rods *g* from the levers *d* after each printing movement and automatically connecting same again after the printing-plate has received two applications of color. 45

2. In a printing-press in which the printing-plate is carried on a reciprocating carriage, oscillating levers *d* adapted to reciprocate the carriage, pins *n* on the levers, connecting-rods *g* provided with gabs which engage the pins, and means for automatically disconnecting the rods *g* from the levers *d* after each printing movement and automatically connecting same again after the printing-plate has received two applications of color, 55 said means comprising the arms *k* *p*, shaft *r*, segment-levers *z* *y*, shaft *u*, lever *v*, and cam-disk *s*, which latter only is adapted to rotate 60 once while the main shaft is effecting two revolutions. 65

In testimony whereof I have affixed my signature in presence of two witnesses.

HANS FOMM.
